UNITED STATES PATENT OFFICE.

MARY LOUISE MOCHON, OF LEAD, SOUTH DAKOTA.

GAUZE-ROLLER.

1,270,188.

Specification of Letters Patent. Patented June 18, 1918.

Application filed February 21, 1918. Serial No. 218,516.

To all whom it may concern:

Be it known that I, MARY LOUISE MOCHON, a citizen of the United States, residing at Lead, in the county of Lawrence and State 5 of South Dakota, have invented certain new and useful Improvements in Gauze-Rollers; and I do hereby declare the following to be a full, clear, and exact description of the invention, such as will enable others skilled 10 in the art to which it appertains to make and use the same.

My invention relates to improvements in gauze rollers and has for one of its objects the provision of a roller upon which the 15 gauze may be uniformly and tightly rolled.

Another object of this invention is to provide a roller so constructed as to permit it to be removably attached to a length of gauze and rolled upon a table whereby the 20 gauze will be tightly and uniformly rolled.

A further object of this invention is to provide a gauze roller which will eliminate waste due to the fact that the gauze will be properly and tightly rolled for use as a 25 surgical dressing.

A still further object of this invention is to provide a gauze roller of this character, which will be simple, practical and comparatively inexpensive in construction, and one 30 than can be manufactured and sold at a low cost.

With these and other objects in view, the invention consists of certain novel features, combination and arrangement of parts hereinafter more fully described and set forth in the claims hereto appended.

In the drawing:

Figure 1 is a side elevation of the handles partly in section illustrating the roller assembled and ready for use.

Fig. 2 is a side elevation illustrating the roller disconnected and ready to be applied to the gauze to roll the same.

Fig. 3 is a transverse sectional view taken 45 on the line 3-3 of Fig. 1 looking in the direction indicated by the arrows.

Like numerals of reference designate corresponding parts in all the figures of the drawing.

Referring to the drawing, the numeral 5 indicates a pair of handles which are substantially cylindrical in cross section. The handles are formed of wood or any other material suitable for the purpose.

55 Each handle has one end enlarged as at 6, which enlargement terminates into a cir-

cular head 7, the enlargement 6 being concentric with relation to its respective head 7. The heads 7 are provided with a pair of relatively spaced inwardly extending bores 8, 60 which bores have their inner ends terminating into the handles 5.

A cylindrical pin 9 has one end removably secured in one bore of each head and handle respectively. The pins are formed of steel 65 or other suitable non-rusting material and are of sufficient length to compensate for the standard type of gauze to be rolled. The free end of each pin is adapted to enter the other bore of each head and handle when 70 said handles are moved longitudinally in the direction of each other thereby removably connecting the handles together in gauze rolling position.

It is to be understood that the diameter 75 of the pins is as large as the diameter of the bores so that when the pins are fitted within said bores they will be held therein against accidental displacement under ordinary conditions.

In use, the gauze to be rolled is folded according to the directions given in the War Manual, and the gauze after being folded is laid upon a table and has one end fastened thereto by arranging a piece of wood over 85 the gauze and fastening it to the table with a suitable clamp. The handles are then disconnected, leaving a pin in each handle.

One pin is laid transversely across the upper side of the gauze and the other pin is arranged on the under side of the gauze adjacent the free end thereof. The handles are then moved longitudinally in the direction 90 of each other and the free end of each pin moved into the bore of each handle until the 95 opposite sides of the gauze are in contact with the opposing faces of the circular heads of the handles. The roller is now in position to start to roll along a table and wind up the gauze upon the pins. By rolling 100 along the table in the direction of the clamp the gauze will be wrapped about the pins and by pulling slightly in the direction of the person operating the roller on the table the gauze will be tightened upon the roller. 105

After the gauze has been completely rolled, the handles are removed from their respective pins and the pins removed from the gauze and the said gauze is tied.

Having thus described my invention what 110 I claim is:

1. A gauze roller comprising a pair of

handles each having one end enlarged and terminating into a circular head, which heads are each provided with a pair of relatively spaced inwardly extending bores, a 5 pin removably carried by each head having one end fitted in one of the bores and the free end of each pin adapted to be moved into the other bore of the adjacent handle, said circular enlargements permitting the 10 handles to be rolled along a table top or other support, as and for the purpose specified.

2. A gauze roller comprising a pair of handles having one end terminating into 15 circular enlargements constituting rollers whereby the handles may be rolled along a

table top or support, each enlargement provided centrally with a pair of spaced inwardly extending bores which terminate in the handles, a pin having one end removably 20 arranged in the bore of each handle, and said pins adapted to removably connect the handles together and receive gauze thereon when the handles are rolled upon a table top, as and for the purpose specified.

25 In testimony whereof I affix my signature in presence of two witnesses.

MARY LOUISE MOCHON.
